UNDER-GARMENT

Philip H. Robbins, New York, N. Y., assignor to
Poirette Corsets, Inc., New York, N. Y.

Application May 28, 1936, Serial No. 82,352

4 Claims. (Cl. 2—30)

This invention relates to an undergarment, and has for its object to provide, in a manner as hereinafter set forth, a garment of the class referred to including as an element thereof a continuous resilient strap consisting of a U-shaped rear stretch anchored at its lower end to the back of the garment body and a pair of spaced upstanding front stretches forming continuations of the sides of the rear stretch anchored at their lower ends to the front of the body of the garment, and with said element providing, when the garment is worn for perfect back and shoulder control; for shoulder straps; for controlling under arm purchase; for insuring perfect bust control; for giving an extreme high or low back and at the same time controlling the diaphragm; for distributing strain equally over its entire length; for tending to hug a hollow back; for eliminating any possibility of the back of the garment binding; for distributing the pull equally at all points; for tending to give a backward pull and support to the diaphragm and bust; and for tending to control the waistline below the shoulder blades and also forms into the hollow of the back whereby at all times in standing, sitting or bending position, it will hug the body.

Further objects of the invention are to provide, in a manner as hereinafter set forth, a garment for the purpose referred to which is simple in its construction and arrangement, strong, durable, compact, thoroughly efficient in the use intended thereby, readily assembled and comparatively inexpensive to manufacture.

To the above ends and to others which may hereinafter appear, the invention consists of the novel construction and arrangement of parts as will be more specifically described and are as illustrated in the accompanying drawing wherein is shown an embodiment of the invention, but it is to be understood that changes, variations and modifications may be resorted to which fall within the scope of the invention as claimed.

In the drawing:

Figure 1 is a fragmentary view in perspective simulating the back of the wearer of the garment and further showing the garment in position,

Figure 2 is a view similar to Figure 1 looking towards the front of the wearer of the garment with the latter in position,

Figure 3 is a fragmentary view in rear elevation of the upper portion of the garment-back in non-extended position,

Figure 4 is a section on line 4—4, Figure 2, and

Figure 5 is a fragmentary view upon an enlarged scale and in rear elevation of the upper

portion of the garment-back illustrating a cat stitching forming an extendible and contractible coupling means between the garment back and the elastic strap-like element.

The garment shown is of the girdle and brassière type and has its body generally indicated at 6. The body 6 is formed of an upper section 7 providing a brassière and a lower section 8 forming a girdle. The section 8 is of greater length than section 7. The section 8 is preferably formed from closely knit fabric. The bottom of section 7 is secured to and throughout the top edge of section 8. The body 6 includes a front, a pair of sides and a back indicated at 9, 10, 11, and 12 respectively. The section 7 throughout is preferably formed of lace or a net-like fabric shaped in a manner at its front to form the upper part of the front 9 as a bust covering portion 13 provided with a pair of tapered parts having their apices indicated at 14, 15. The apices of said parts are located in spaced relation with respect to the lengthwise median of the front of body 6 and the sides 10, 11. That part of the section 7 which provides the upper portion of the back 12 and indicated at 16 has a segmental shape 25 cutout 17 which forms a notch having its mouth opening at and adjacent the ends of the top edge of back 12. The notch, formed by the cutout 17, when the garment is worn appears as of substantially U-shaped contour.

The garment includes a continuous resilient element 18 of strap-like form provided with a U-shaped rear stretch 19, a pair of spaced intermediate stretches 20, 21 forming continuations of the upper ends of the sides of the stretch 19 and a pair of front stretches 22, 23 forming depending continuations of the stretches 20, 21 respectively.

The lower portion of the stretch 19 is indicated at 24 and it is extended in the notch formed by the cutout 17 in proximity to the edge of the latter. The upper ends of portion 24 of stretch 19 are secured to the part 16 by two spaced pairs of parallel securers which are anchored to the sides of stretch 19 and to the part 16 at the ends 45 of the cutout 17. The securers of one pair are indicated at 25 and those of the other pair at 26. The part 16 is hemmed as at 26a. The outer edge of the portion 24 of stretch 19 is connected to the hem 26a by a contractible and expandible coupling means 27 in the form of cat stitching. That portion of the part 16 bordering the edge of the cutout 17 is fulled on the lower portion 24 of the stretch 19 by the coupling means 27 to provide for the expansion of the garment when worn to 55

- smooth out the top of part 16 and for contraction when the garment is not in use. The top edge of the lower portion 24 of stretch 19 is normally buckled as at 28 to provide for a smooth effect of portion 24 when the latter is extended.
- The lower end of each of the front stretches extends between the folds 29, 30 of a folded strap 31. The fold 29 has its upper end arranged between the rear face of part 13 and an inwardly turned portion 32 (Figure 4) of the part 13. The lower end of each front stretch seats upon the bend 33 between the folds 29, 30. The upper ends of the folds, portion 32, a front stretch and part 13 are secured together by stitching 34.
- Adjacent the lower ends of the folds and front stretch, they are secured together and to the part 13 by the stitching 35. The foregoing arrangement provides for securing the elastic element to the front of the garment.
- The intermediate stretches 20, 21 provide suspensions on the shoulders for the garment.
- The manner of setting up the element 18 relative to the back and front of the garment provides the advantages as heretofore referred to.
- What I claim is:
1. A woman's undergarment comprising a body formed of brassière and a girdle, the front of the brassière being formed at its upper portion with a pair of tapered parts having their apices spaced adjacent to opposed sides of the lengthwise median of the front of said body, the back of the brassière being formed in its top edge with a cutout providing a notch having its mouth spaced from the ends of said edge, an elastic element of strap-like form including an upstanding U-shaped rear stretch, a pair of intermediate stretches forming shoulder extensions and forward continuations of the sides of the rear stretch and a pair of front stretches forming depending continuations of the intermediate stretches, the lower portion of said rear stretch extending into said notch, means for connecting the bottom edge of said lower portion of the rear stretch with the edge of said notch, and means for securing the lower end terminal portions of the front stretches to the apices of said tapered parts.
  2. A woman's undergarment comprising a body formed of brassière and a girdle, the front of the brassière being formed at its upper portion with a pair of tapered parts having their apices spaced adjacent to opposed sides of the lengthwise median of the front of said body, the back of the brassière being formed in its top edge with a cutout providing a notch having its mouth spaced from the ends of said edge, an elastic element of strap-like form including an upstanding U-shaped rear stretch, a pair of intermediate stretches forming shoulder extensions and forward continuations of the sides of the rear stretch and a pair of front stretches forming de-

pending continuations of the intermediate stretches, the lower portion of said rear stretch extending into said notch, means for connecting the bottom edge of said lower portion of the rear stretch with the edge of said notch, means for securing the lower end terminal portions of the front stretches to the apices of said tapered parts, and means for anchoring the upper ends of said lower portion to the end terminal portions of the edge of said notch.

3. A woman's undergarment comprising a body part formed of a front, a pair of sides and a back, said back being formed with a cutout to provide a notch opening at the top edge thereof, said front being formed at its upper portion with a pair of tapered parts having their apices spaced adjacent to opposite sides of the lengthwise median thereof, an elastic element of strap-like form including a rear stretch corresponding in contour to and of greater length than the depth of said notch, a pair of spaced intermediate stretches forming shoulder suspensions and forward continuations of the sides of the rear stretch and a pair of spaced front stretches forming depending continuations of the intermediate stretches, the lower portion of the rear stretch extending into said notch, a contractible and expandible coupling means connecting the outer edge of said lower portion of said rear stretch with the edge of said notch, and means for securing the lower end terminal portions of said front stretches to the apices of said tapered parts.

4. A woman's undergarment comprising a body part formed of a front, a pair of sides and a back, said back being formed with a cutout to provide a notch opening at the top edge thereof, said front being formed at its upper portion with a pair of tapered parts having their apices spaced adjacent to opposite sides of the lengthwise median thereof, an elastic element of strap-like form including a rear stretch corresponding in contour to and of greater length than the depth of said notch, a pair of spaced intermediate stretches forming shoulder suspensions and forward continuations of the sides of the rear stretch and a pair of spaced front stretches forming depending continuations of the intermediate stretches, the lower portion of the rear stretch extending into said notch, a contractible and expandible coupling means connecting the outer edge of said lower portion of said rear stretch with the edge of said notch, means for securing the lower end terminal portions of said front stretches to the apices of said tapered parts, and oppositely extending spaced means for anchoring the upper ends of the said lower portion of the rear stretch to the end terminal portions of the edge of said notch.
